ENVELOPE

Willard E. Swift, Worcester, Mass., assignor to
 United States Envelope Company, Springfield,
 Mass., a corporation of Maine

Application January 2, 1943, Serial No. 471,114

2 Claims. (Cl. 229—84)

The present invention relates to envelopes of the type in which closure is effected by means of the insertion of an integral tongue through registering perforations provided in overlying flap and body portions of the envelope, whereby the flap is locked in position by the inserted tongue.

Such an envelope is exemplified by Trenchard Patent No. 1,519,567, dated December 16, 1924, in accordance with which the locking tongue, by a transverse fold back of its material, is made of double thickness, to increase the stiffness thereof.

The envelope of my invention provides an improved construction for this integral double-thickness locking tongue, by which to make it far more durable in its zones or portions of greatest wear, and far less liable to disintegration by the parting or separation of its two constituent plies of envelope material, under the flexings involved in repeated openings and closings of the envelope. In this latter respect my improved envelope provides a satisfactory substitute for various types of metallic fastener envelopes no longer available during the present emergency.

The above and other advantageous features of the invention will hereinafter more fully appear from the following description, considered in connection with the accompanying drawing, in which—

Fig. 1 is a plan view showing the blank from which is made the envelope of my invention.

Fig. 2 is a rear view of the completed envelope, with the closure flap in open position.

Fig. 3 is a vertical sectional view through the envelope, with the flap locked in closed position.

Referring first to Fig. 1, the blank from which my improved envelope is made comprises a rectangular body portion 1 as inclosed by dot and dash lines, the said body portion constituting the envelope's front wall; projecting from said body portion 1 are side flaps 2 and 3, a bottom flap 4, and a closure flap 5. In cutting the blank, the side flap 2 and closure flap 5 are provided with slots 6 and 7, respectively, so positioned that when the flap 5 is folded over to close the completed envelope of Fig. 2, its slot 7 will register with the slot 6 provided in the envelope's back wall by the side flap 2. The flap 5 is preferably formed with an extension 8 beyond a fold line 9, and this extension provides a slot 10 for registration with the slot 7 when the extension is folded over along the line 9, as shown in Fig. 2.

In the rear wall of my improved envelope as shown by Fig. 2, the side flap 3 makes an ap-

preciable overlap of the side flap 2; in the envelope blank (Fig. 1), the flap 3 is cut to a width considerably greater than needed for this overlap, such extra width being provided by a lateral extension 3a, beyond the line 14, Fig. 1. Inwardly of said line 14, the flap 3 is formed with a slit 11 opening downwardly from the upper edge of said flap, which edge beyond said slit is preferably constituted by converging lines 12 and 13 which meet at an angle that is bisected by the line 14.

In making my improved envelope from the blank of Fig. 1, that portion 3a of the flap 3 beyond the line 14 is folded over on said line to make the flap of double thickness beyond the slit 11, the two thicknesses or plies of the flap being secured together by suitable adhesive 15 applied to the flap before the fold is made. The extension 8 of closure flap 5 is similarly folded along line 9 to bring the perforations 7 and 10 into registration, with the overlying portions of the flap being secured together by previously-applied adhesive 16. Following this initial folding and adhesion which gives double thickness to portions of the flaps 3 and 5, the blank is conventionally folded and its overlapping flaps adhered to form the completed envelope of Fig. 2; that is to say, the first fold-over is of flap 2, followed by a fold-over of flap 3 which overlaps at its outer edge (the fold 14) upon a portion of flap 2—portions of said overlapping areas being united in this operation by an area of suitable adhesive 17 (Fig. 1) to incorporate said edge 14 in a central back wall seam, whose upper terminal is at or below the level of the bottom of slot 11. Then the flap 4 is folded over and secured by adhesive 18 to the lower edges of the flaps 2 and 3, to form the envelope's bottom closure, and to complete the envelope pocket.

Thus in the completed envelope the upper portion of flap 3, between slit 11 and edge 14, is left unsecured to flap 2 and forms a double-thickness locking tongue 19 for cooperation with the slots 6 and 7 of back wall and closure flap, respectively. In so using the envelope after insertion therein of the contents, the tongue 19 is flexed back, and the closure flap 5 is folded down, thereby bringing its slots 7 and 10 into register with the rear wall slot 6. In order to lock the flap 5 in closed position, the tongue 19 is seized and flexed sufficiently to enter its upper edge in the registered slots 6, 7 and 10, so as to lie behind the rear wall flap 2 above said slots, as is evident from a consideration of Fig. 3.

The above described construction of a double-

thickness locking tongue 19 is particularly effective in enabling said tongue to withstand the wear and abuse involved in its repeated flexures and its back and forth movements through the slots, in the frequent locking and unlocking of the closure flap 5. Repeated flexures of such a two-ply element invariably tend to destroy the adhesive connection at the base of the tongue (the zone of maximum flexure) between the layers of material, but in my envelope the tongue element suffers no actual separation or appreciable loss of stiffness from such disintegration of the adhesive bond, because in the completed envelope the flap extension 3a which provides the tongue's reinforcement is not exposed on the outside of the envelope, but is an underneath interior fold, so arranged as to remain in tongue-stiffening position despite any loosening of the adhesive connection. It is to be noted further that customary manipulations of such a tongue, for insertions into and withdrawals from the slots of the back wall and closure flap, involve rubbing contact between the tongue's right-hand longitudinal edge and the end portions of said slots; but in my improved reinforced tongue construction, the fact that this edge is constituted by a fold of the material rather than by the individual edges of two layers of material, makes for far greater resistance to fraying of said edge under repeated rubbings against the end portions of said slots. In addition, this tongue reinforcement by a longitudinal rather than a transverse fold gives opportunity, without waste of material, to provide said tongue at its end with a point 20, for greater ease of entering it in the registered slots of closure flap and rear wall--this resulting from the angle between edge portions 12 and 13 of flap 3a, which is bisected by the fold line 14 as previously described.

I claim:

1. An envelope having a pocket portion and a

slotted closure flap, said pocket portion having a front wall and a rear wall, the latter comprising two opposite side flaps and a bottom flap, said three flaps being folded inwardly and adhesively connected to each other in mutually overlapping areas, one of said side flaps having a slot with which registers the slot of said closure flap when the latter is folded down to pocket-closing position, the second side flap having a slit extending inwardly from its upper edge to provide an integral tongue for insertion through the so-registered slots, and a reinforcement for said tongue, comprising an integral lateral extension on said second side flap, said extension being folded under between said two side flaps and adhered to said tongue to double its thickness, the line of said fold running longitudinally of said tongue and constituting one of its longitudinal edges.

2. An envelope having a pocket portion and a slotted closure flap, said pocket portion having a front wall and a rear wall, the latter comprising two opposite side flaps and a bottom flap, said three flaps being folded inwardly and adhesively connected to each other in mutually overlapping areas, one of said side flaps having a slot with which registers the slot of said closure flap when the latter is folded down to pocket-closing position, the second side flap having a slit extending inwardly from its upper edge to form an integral tongue for insertion through the so-registered slots, and a reinforcement for said tongue comprising an integral lateral extension of said second side flap, said extension being folded upon and adhesively secured to said tongue to double its thickness, the line of said fold running longitudinally of said tongue and constituting one of its longitudinal edges, the upper edges of said second side flap and its lateral extension standing at an angle which is bisected by said line of fold, to give said tongue a point at one of its corners.

WILLARD E. SWIFT.
